UNITED STATES PATENT OFFICE.

EDWARD GOLD, OF VANCOUVER, BRITISH COLUMBIA, CANADA.

MACHINE FOR IMPARTING SPIRAL MOVEMENT TO PILES.

No. 868,839.

Specification of Letters Patent.

Patented Oct. 15, 1907.

Application filed August 20, 1906. Serial No. 381,368.

To all whom it may concern:

Be it known that I, EDWARD GOLD, a citizen of the United States of America, residing at the city of Vancouver, in the Province of British Columbia, Canada, have invented a new and useful Improvement in Machines for Imparting Spiral Movement to Piles, of which the following is a specification.

This invention relates to a machine for applying a spiral wrapping to piles, and comprises a rotatable head having radially operated means for securing the pile concentrically within it, means for rotating such head, and means for endwise moving the carriage on which the rotatable head is mounted whereby a spiral movement is imparted to the pile; and in combination therewith a tail carrier for supporting the other end of the pile, which carrier is provided with means whereby the supporting rollers are adapted to varying dimensions of piles.

The invention is fully set forth in the following specification, reference being made to the drawings by which it is accompanied, in which:

Figure 1, is a side elevation showing the general arrangement of the head and tail carrier, Fig. 2, an end elevation of the head to an enlarged scale, taken in the direction of the arrow in Fig. 1, Fig. 3, a side elevation of the same, the upper part of the rotatable head being shown in section on the line A in Fig. 2, Fig. 4, a section of the rim of the head on the line B in Fig. 2, Fig. 5, a detail of the yoke which connects the gear clutches of the driving mechanism, Fig. 6, a detail showing the driving gear of the rotatable head in end elevation, Fig. 7, a side elevation of the same, showing also the connection therewith of the carriage driving gear, Fig. 8, a vertical cross section and end elevation of the tail carrier on the line D D in Fig. 9, and, Fig. 9, a vertical section and side elevation of the same on the line C C in Fig. 8. Fig. 10, is a detail view of a modification of my invention hereinafter again referred to.

In these drawings 2 represents the pile about which a spiral wrapping 9 is to be applied, and 3 the cylindrical rotatable head within which the pile is secured, and through which the desired movements are imparted to it. This head 3 is provided with circumferential V-shaped grooves 4 in its outer surface, in which grooves 45 the head is rotatable on rollers 5 mounted in a carriage frame 6, which is provided with flanged wheels 7 to run on track rails 8. A flared mouth ring 10 is fitted within the cylindrical head 3 so as to be endwise movable, rotation within the head being prevented by a feather key or keys 11.

Pivotal mounted on pins 12 on the inner side of the mouth ring 10, and on corresponding pins 13, on an inwardly directed flange 14 at the back end of the cylindrical head 3 is a series of links 15 connected in pairs by pins 16, the free ends 17 of which links are rounded and beveled that they will enter into and obtain an

efficient driving hold on the wood of a pile placed within the mouth ring 10. The links 15 are operated to secure a pile by the retraction within the cylindrical head 3 of the mouth ring 10 which movement by bringing the anchoring pins 12 and 13 of the link system together, forces the sharpened ends 17 of the links radially inward on the arcs indicated in Fig. 3 and they will thus center and securely hold the pile. The endwise movement of the mouth ring 10 is effected by a series of screws 20, see Fig. 4 each threaded into the mouth ring and rotatable between collars in the back flange 14 of the rotatable head 3.

The screws 20 are simultaneously operated to effect the endwise movement by pinions 21 secured to the outwardly projecting back end of each screw 20, the teeth of which pinions mesh with the internal teeth of a gear ring 22 rotatable on a bearing ring 23 projecting from the back plate of the flange 14 of the rotatable head, which bearing ring fits into a corresponding annular groove in the gear ring 22. The gear ring 22 is also provided with external teeth by which it is rotated by a pinion 25, secured on a shaft 26 rotatable in a bearing 27 secured to the carriage frame 6; the shaft 26 being rotated by a worm gear 28 from the shaft 29 of the motor 30 which operates the general mechanism of the carriage and its head. This worm gear is driven through a conical friction clutch operated by a hand lever 31 so that undue pressure will not be thrown on the centering and securing mechanism. The head 3 itself is rotated by means of a pinion 32 the teeth of which mesh with teeth 33 round the after part of the cylindrical head, and the shaft 34 on which this pinion 32 is secured, is driven by bevel wheels 38, 39 from an intermediate shaft 37 which again is driven from the motor shaft 29 by a pinion 35 on 29 meshing with a wheel 36 on the intermediate shaft 37. The bevel 39 runs free on the intermediate shaft 37 and is connected to drive it by means of the clutch 40 endwise slideable on a feather key in the shaft and operated in and out of driving contact by the lever 41.

The shaft 34 which rotates the head by means of the pinion 32 also carries a worm 45 designed to drive through a worm wheel 47 the driving axle 46 of the carriage 6. This worm wheel 47 runs free on the axle 46 and is connected to drive the shaft 46 by a clutch 48 slideable on a feather in the axle. This traveling gear is designed to move the carriage forward at such a rate of speed in proportion to the rotation of the head that will impart the desired spiral movement to the pile. As it may be necessary however to move the carriage at a higher rate of speed when the rotation of the head is not required, as when the wrapping having been applied the pile is being run out to deliver, I provide gear wheels 50 and 51 on the intermediate shaft 37 and the driving axle 46 respectively. As this gear must be out of action when the wrapping gear is

- in operation, the wheel 50 is free on the intermediate shaft 37 and is rotatably secured thereto by a clutch face 52 on the same keyed clutch 40 which connects the bevel gear to the shaft 37. To insure that the 5 slow speed gear through the worm 45 and worm wheel 47 is disconnected before the axle 46 is connected to be driven through the gears 50 and 51, the clutches 40 and 48 are connected so as to be operable together by the lever 41, by a yoke 53 engaging the grooves of the 10 clutch members, to which yoke the lower end of the lever 41 fulcrumed at 42 on the sector 43 is connected, as shown in Fig. 2. By this means when the lever 41 is in the position shown in Fig. 2 of the drawing the motor 30 will rotate the head 3 and drive the axle 46 15 to move the carriage 6 on the tracks 8 at the desired speed to apply the wrapping, as the beveled gear 39 is then clutched to the shaft 37 and will rotate the pinion shaft 38 and the worm wheel 34 on that same shaft is clutched to drive the axle 46.
- 20 If the lever 41 is in the central position on the sector 43, both the bevel wheel 39 and the worm wheel 47 are free on their axles and the motor 30 may be used to secure or release the pile securing device in the rotatable head through the medium of the worm gear 28 25 and shaft 26. If again the lever is moved over to the pin hole on the extreme left of the sector 43, the bevel gear 39 and worm wheel 45 are still free but the face 52 of the clutch 40 is moved into the recessed engagement of the gear wheel 50 on the intermediate shaft 37 30 and drives the axle 46 at the higher rate of speed through the gear wheel 51 secured on it. Although this particular method of driving has been specifically described it is not a material point of the application as the same results may be attained by a different 35 mechanism.
- The tail carrier illustrated in Figs. 8 and 9 of the drawings consists of rollers 55 rotatably mounted on a mechanism to be described and having peripheral ridges 54 to engage the wood of the pile 2 and insure 40 that the carriage travels with the pile. The mechanism which carries the roller is supported in a suitable box frame 56 on a carriage 57 mounted on flanged wheels 58 to run on the tracks 8. The rollers 55 are elevated or depressed to raise or lower and to center 45 a pile in the axis of rotation of the machine, by mounting the rollers on pins 59 between two linked lever systems. This mechanism is composed of levers 60 connected toward their upper ends to the axial pins 59 of the rollers and at their mid length on a pin 61 secured 50 in the sides of the box frame 56. To pins 62 in the lower ends of the levers 60 and to the roller axial pins 59, short links 63 connect the lower and upper ends of the levers 60 at each side of the center pin 61 respectively to pins 64 laterally projecting from nuts 65 on right and left hand threads of a screw 66 rotatable in the ends of the box frame 56 by means of a crank handle 67. The screw 66 passes through and is rotatable in a member 68 from which the center pin 61 projects on each side of the screw, so that the weight of the 60 pile which rests on the carrier is transmitted to the frame 56 through this center bearing member 68, and through the end bearings of the screw 66. The upper ends of the levers 60 may be extended upward beyond the rollers and inwardly curved as at 68 to form guards 65 to prevent the pile falling off the rollers 55.
- In the operation of the device, a pile being slung from an overhead carrier or otherwise suitably supported, the tail carrier 57 is run under one end and its rollers 55 are by means of the crank handle 67 adjusted to center and sustain the weight of that end of the pile. The 70 head carriage 6 is then moved on the tracks up to the other end, and the end of the pile is directed within the rotatable head 3 by the flare of the mouth ring 10. The clutch lever 41 being set in the mid position, where the traveling and rotating mechanism is unclutched, the 75 motor 30 is started and by means of the lever 31 the gear ring 22 is rotated through the friction clutch 28^a, and operates the several screws 20 to draw the mouth ring 10 inward and the sharpened ends 17 of the linked levers 15 are radially driven into the pile centering it in 80 and securing it to the rotatable head 3. The temporary sling or support is then removed and the pile is sustained in the head and tail carriages 6 and 57. The lever 41 is then thrown over to the extreme left to simultaneously clutch the bevel gear 39 to rotate the head 3 85 with its secured pile, by means of the pinion 32, and the worm wheel 47 to travel the carriage at the slow speed, by means of the driving axle 46. The combined movement thus imparted to the pile gives the desired spiral movement to it which is the object of the device. On 90 the operation being completed for which the movement is required, the lever 41 is thrown over to the extreme right which unclutches the rotating and the slow speed gear and brings the face 52 of the clutch into engagement with the corresponding recessed clutch face 95 of the gear wheel 50 and the carriage is traveled along the track at the higher speed to deliver the finished pile. The lever 41 is then placed in the central position which frees the clutches from contact with the rotating and traveling gear of the head, and the movement of the motor 30 being reversed the gear ring 22 is 100 operated by the lever 31 to release the centering ends 17 from the pile end and the pile is free to be removed.
- If found necessary instead of driving the carriage 6 through the adhesion of its wheels 7 on the track the 105 wheels 7 may be free on the axle 46 and the movement imparted to the carriage by pinions secured on the axle which pinions 146 will gear into racks 147 alongside the track rails 8 as shown in Fig. 10.
- Having now particularly described my invention and 110 the manner of its operation I hereby declare that what I claim as new and desire to be protected in by Letters Patent is:
1. In a device of the class described, the combination with a carriage endwise movable, of a cylindrical driving head rotatable in the carriage, means secured to the carriage for rotating the cylindrical head and for simultaneously traveling the carriage, and means for stopping the rotation of the head while permitting the carriage to continue traveling, substantially as shown and described. 115
  2. In a device of the class described, the combination with a carriage endwise movable on wheels, of a cylindrical driving head rotatable on rollers in the carriage, radially operative means for centering and securing a pile within the head, means for rotating the cylindrical head 120 and means for endwise traveling the carriage. 125
  3. In a device of the class described, the combination with a carriage endwise movable on wheels, of a cylindrical driving head rotatable on rollers in the carriage, a flared mouth ring endwise movable within the cylindrical head, a series of link levers pivotally connected round the inner side of the cylindrical head, a corresponding series of levers pivotally connected to the adjacent side of the 130

mouth ring said opposed levers on head and mouth ring being pivotally connected in pairs to one another at about their mid length, means for radially operating the free ends of the linked levers by endwise movement of the 5 mouth ring within the cylindrical head, means for rotating the head, and means for simultaneously traveling the carriage endwise whereby a spiral movement is imparted to a pile secured in the head.

4. In a device of the class described the combination 10 with a carriage mounted on wheels so as to be endwise movable on a track, of a cylindrical head rotatable on rollers in the carriage frame, a mouth ring endwise slideable within this cylindrical head, a series of levers having flattened and sharpened ends pivotally connected to the 15 head around its inner side, similar levers pivotally connected to the adjacent side of the mouth ring, the opposite levers being pivotally connected together in pairs at approximately their mid length, means for endwise moving the mouth ring within the cylindrical head such means 20 comprising a series of screws rotatable in the back end of the cylindrical head and threaded into the mouth ring, means for rotating such screws such means comprising, pinions secured to the back end of each screw, a gear ring rotatable on the back end of the cylindrical head said 25 gear ring having internal teeth adapted to mesh with the teeth of the several pinions secured to the screws and external teeth, a pinion the teeth of which mesh with the external teeth of the gear ring, and means for rotating the pinion through a friction clutch from a motor on the carriage.
5. In a device of the class described, a wheeled carriage 30 having a cylindrical head rotatable on rollers in the carriage frame, means for centrally securing or releasing a pile within the cylindrical head, said means being operative from a motor on the carriage, means for disconnecting such operative means from the motor, means for simultaneously rotating the head and traveling the carriage by the motor, means for disconnecting such rotating and traveling mechanism, and means for alone traveling the 35 carriage at a higher rate of speed.

6. In a device of the class described, a wheeled carriage endwise movable on tracks, said carriage having a cylindrical head rotatable in the carriage and having means for centrally securing one end of a pile therein, means for supporting the other end of the pile, such means comprising a wheeled carriage having rollers on which the end of the pile may rest, means for preventing endwise movement of the pile on the rollers, and means for elevating and depressing the rollers and for simultaneously lessening and increasing the distance of the rollers apart. 45

7. In a device of the class described the combination 50 with an endwise movable carriage, wheels upon which said carriage is mounted, of a cylindrical driving head, rollers mounted on the carriage upon which said driving head is rotatable, means secured to the carriage for rotating the cylindrical head and for simultaneously traveling the carriage, and means for stopping the rotation of the head at 55 times while permitting the carriage to continue traveling substantially as shown and described.

8. As a means for imparting a spiral movement to a 60 pile or article of similar form, the combination with a carriage endwise movable on a track, of a cylindrical driving head rotatably mounted in the frame of the carriage, a plurality of radially arranged levers for centering and securing the pile within the head, substantially as shown 65 and described.

9. As a means for imparting a spiral movement to a 70 pile or article of similar form, the combination with a carriage endwise movable on a track, of a cylindrical driving head rotatably mounted in the frame of the carriage, a plurality of radially arranged levers for centering and securing the pile within the head and means for simultaneously operating all of said levers, substantially as shown and described.

In testimony whereof I have signed my name to this 75 specification in the presence of two subscribing witnesses.

EDWARD GOLD.
